UNITED STATES PATENT OFFICE.

HOMER A. BRETZ, OF JACKSON, MICHIGAN, ASSIGNOR TO MINERALLAC ELECTRIC COMPANY, OF CHICAGO, ILLINOIS, A CORPORATION OF ILLINOIS.

AUTOMOBILE-HORN.

1,157,292.

Specification of Letters Patent.

Patented Oct. 19, 1915.

Application filed December 28, 1914. Serial No. 879,267.

To all whom it may concern:

Be it known that I, HOMER A. BRETZ, a citizen of the United States, and a resident of Jackson, in the county of Jackson and State of Michigan, have invented certain new and useful Improvements in Automobile-Horns; and I do hereby declare that the following is a full, clear, and exact description thereof, reference being had to the accompanying drawings, and to the letters of reference marked thereon, which form a part of this specification.

This invention relates to improvements in automobile horns and consists of the matters hereinafter described and more particularly pointed out in the appended claims.

The object of this invention is to produce an electrically operated horn, particularly adapted for use in connection with an automobile, consisting of a small number of parts, which may be readily and easily assembled in a compact arrangement, said arrangement being such as will permit the same screws which retain the casing together, to secure the operating parts of the horn within said casing in proper relative position with respect to each.

Another object of my invention is to produce a horn wherein the number of moving parts therein is reduced to a minimum, eliminating breakage and disarrangement of the parts, thus increasing the usefulness and life of the horn.

Other objects and advantages will appear as I proceed with my specification.

In the drawings: Figure 1 illustrates a longitudinal central vertical sectional view through an automobile horn made in accordance with my invention, the plane of the section being indicated by line 1—1 of Fig. 2. Fig. 2 illustrates a view in rear elevation of my improved horn. Fig. 3 illustrates a transverse vertical sectional view through my improved horn, the plane of the section being indicated by the line 3—3 of Fig. 1. Fig. 4 illustrates a longitudinal vertical sectional view through my improved horn, the plane of the section being indicated by the line 4—4 of Fig. 3.

Referring to that embodiment of my invention as illustrated in the accompanying drawings, 10 indicates a cup-like casing having an annular flange 11. Said casing is preferably made of sheet metal and is

adapted to contain an annular magnetic coil 12, a thin sheet of insulating material 13, such as fiber being interposed between the flat wall of said casing and said coil. The coil 12 is retained in position within said casing by means of a dished ring 14 which has a peripheral marginal edge 14^a engaging and coinciding with the marginal flange of the casing 10. The inner peripheral marginal edge of said dished ring is offset from the plane of the marginal edge 14^a and engages with one face of the coil 12 to securely hold the same in proper position within the casing. The ring 14, in this instance, forms a part of the magnetic field of the coil 12.

15 indicates a thin flat spring made preferably in the form of a disk which engages at its peripheral margin with the margin 14^a of the ring 14, and forms the actuating member of the horn as a whole. Mounted 75 concentrically upon said spring disk and extending into the casing 10 is a cup-like armature 16 of a diameter substantially equal to that of the aperture in the coil retaining ring 14. The armature 16 is fixed to 80 said spring by means of a clamping screw 17, having a head 18 engaging that face of the spring disk 15 opposite the armature 16, the purpose of which will presently appear. A spacing washer 19 surrounds said set 85 screw intermediate the spring 15 and the armature 16 and lock nuts 20 securely clamp said armature in position relative to said spring. Carried upon the inner end of said screw 17 but insulated therefrom by means 90 of a suitable bushing 22 is a contact pin 23. During the operation of the horn said contact pin strikes against a spring contact member 24 intermediate its ends.

The contact member 24 is made in the 95 form of a flat spring strip, arranged on the vertical median line of the horn and is fixed at one end to a bushing 25 by means of a short screw 26. The bushing 25 is seated in a recess formed in a disk of insulating 100 material 27 attached to the inner face of the flat wall of the casing, concentrically with respect to the cup-like armature 16 and with its innermost face located within the plane of said armature. A screw 28 which extends 105 through the flat wall of the casing and through the disk 27 has screw thread engagement with the interior of the bushing

25 thus securing said parts in proper relative position within the casing. Said screw is provided without the casing with a lock nut and washer 28^a and also serves as a binding post for the attachment of one of the current conducting wires.

30 indicates an arcuate spring contact member made of thin sheet metal, which coacts with the spring contact member 24. 10 Said contact member 30 is arranged in a plane intermediate the plane of the contact member 24 and that of the spring disk 15, and is fixed at one end to a bushing 31 which is seated in a recess formed in the 15 insulation disk 27. A screw 33 and its associated nut 33^a securely clamp said bushing to said disk and at the same time secure said contact spring in proper position relative to the contact spring 24. Each of said 20 contact members 24—30, carry coacting contact points 24^a—30^a respectively.

The contact member 30 is connected in circuit with the field of the magnetic coil 12 by means of a radially extending thin 25 metallic strip 35 (see Figs. 3 and 4) located intermediate said coil and the insulation sheet 13 on the inner face of the flat wall of the casing. Said strip engages at its outer end with the wiring of said coil and 30 at its inner end with the clamping screw 33. Said spring contact member 30 is adjustable toward or away from the spring contact member 24 so that proper contact may be attained between the coacting contact points. 35 For this purpose there is provided a thumb screw 34 which extends through and has engagement within a threaded aperture formed in the flat wall of the casing 10. The inner end of said screw engages against 40 the arcuate spring contact member 30 at a point intermediate its ends and the opposite end of said screw without the casing is provided with knurled head 34^b by means of which said screw may be rotated for purposes of the adjustment before mentioned. 45 A lock nut 34^b is provided without the casing for locking said screw in the proper adjusted position. Radially opposite and in the plane of said strip 35 is a similar strip 50 36 which engages at one end, the wiring of the coil 12. The opposite end of said strip is provided with an interiorly threaded boss 37 which is seated in an aperture 27^a formed in the insulation disk 27. A screw 55 38 similar to the screw 28 before mentioned, extends through the flat wall of the casing 10 and through the said boss 37, so as to have threaded engagement with a nut 39 located in the aperture 27^a. Said screw 38 60 is likewise provided without the casing with a lock nut and washer 38^a, said screw serving as a binding post for the attachment of the other current conducting wire. It is apparent that besides performing the functions 65 as binding posts for the horn as a whole,

said screws also act to rigidly attach said disk 27 to the inner face of the flat wall of the casing.

40 indicates a diaphragm, which is the sound producing or resonant part of the 70 horn. Said diaphragm is made in the form of a disk of thin flexible sheet metal of the same diameter as that of the disk-like spring 15 before mentioned and is spaced therefrom by means of a spacing ring 41. Concentrically mounted on said diaphragm and in axial alinement with the clamping screw 17 is an adjustment screw 42 which in the 75 operation of the horn is adapted to be struck by the head 18 of said clamping screw during the vibrations of the spring disk 15. Said screw 42 is adjustable toward or away from the head 18 of the screw 17 so that proper spacing therebetween may be attained. Lock nuts 42^a, 42^b, are provided 80 for said screw, one on each side of said diaphragm.

45 indicates a concavo-convex, apertured front wall plate which forms a resonant chamber and which is provided with a peripheral marginal flange 45^a adapted to engage with the peripheral margin of said diaphragm 40. The edge 45^b of said margin is upset at right angles to the plane thereof and is arranged to cover and inclose the 95 edges of the casing flange 11, ring 14, spring disk 15, ring 41 and diaphragm 42, respectively, and said parts are all secured in proper relative position by means of screws 46 which pass through the several parts just 100 mentioned (see Fig. 1). The aperture in the said front wall casing is defined by means of a short tubular extension 47, to which an amplifying bell shaped horn member 48 is attached.

The operation of the device is as follows: Assuming that the horn as a whole is fixed to a convenient part of an automobile by means of the usual supporting bracket and is operatively connected through its binding 110 posts 28—38 respectively in an electric circuit, having the usual push button switch such as is carried by automobiles at the present time. When the circuit is closed through the push button switch, the annular coil 12 is 115 energized through the spring contact members 24—30 whose associated contact points 24^a—30^a respectively are normally in engagement. When the coil is thus energized, it will attract the armature 16 and cause the 120 same to move toward the flat wall of the casing against the restraining action of the spring disk 15 to which it is attached. As the armature moves under the attraction of the coil the spring disk 15 is caused to flex 125 in the direction of the attraction until the contact pin 23 carried by the clamping screw 17 engages or strikes against the spring contact member 24 and moves the same out of contact with its associated contact member 130

30. When contact has been thus broken between said contact members, the coil becomes momentarily deenergized and the spring disk 15 being in a flexed position tends to 5 assume its normal position. When so released from the attraction of the coil said spring will flex beyond its normal position and the head 18 of the clamping screw 17 will strike against the set screw 42 carried 10 by the diaphragm 40 thus acting as a hammer. When this screw is so struck, it will be forced outwardly and cause said diaphragm to move outwardly and set a sound wave in motion. During this time the 15 spring contact members have again come into contact with each other and the circuit to the coil is completed. The armature is then attracted and when so attracted will move as before described and break the connection between said contact members. The 20 circuit to the coil is thus successively opened and closed and a series of vibrations is imparted to the spring disk 15 which through its clamping pin 17 will impart a series of 25 rapid vibrations to the diaphragm 40, which are thrown off by said diaphragm in the form of sound waves. Different tones of the sound so produced may be had by adjusting the set screw 42 carried by the 30 diaphragm 40, relative to the head 18 of the clamping screw 17, decreasing or increasing the distance through which said spring 15 will have to flex before striking against said screw. The tone may be varied in another 35 manner and that is by adjusting the spring contact member 30 toward or away from its associated spring contact member 23 by means of the adjusting screw 34 before described. In this manner the amount of 40 flexion through which the spring disk 15 must move before breaking contact between said contact members is regulated, causing longer or shorter vibrations of said disk, thus affecting the rapidity of such vibrations 45 and consequently the sound waves caused by its contact with the resonant diaphragm 18. This adjustment is of great advantage as the tone of the sound produced by the horn may be varied without taking 50 the horn apart and without the use of tools.

It is apparent from the foregoing description that by using an annular magnetic coil I am able to use in connection therewith an armature which when in normal position 55 occupies a space in the plane of said coil and with the cup-shaped armature as illustrated and described, the make and break mechanism of the horn may be located and confined within the plane of said armature. 60 This construction is advantageous in that a fore-shortening in the full length of the horn is permitted and a tidy, neat and compact device is produced.

With the arrangement of the parts 65 described, by mounting said armature in the

manner described upon said spring, I am enabled to greatly reduce the number of parts used and at the same time secure all parts in the proper relative position by the same screws as are used in securing the casing parts together. 70

While in describing my invention I have referred to certain details in construction and arrangement of parts, I do not wish to be limited thereto except as may be pointed 75 out in the appended claims.

I claim as my invention:

1. A horn comprising a cuplike casing, an annular magnetic coil in said casing, a flat disk spring, a cuplike armature carried 80 by said spring, means for attaching said armature to said spring, normally engaging contact members fixed in said casing within the plane of said armature and a resonant diaphragm adapted to be struck by said attaching means. 85

2. A horn comprising a cuplike casing, an annular magnetic coil in said casing, means for retaining said coil in said casing, a flat disk spring, a cuplike armature carried by said spring, means for attaching said armature to said spring, normally engaging contact members fixed in said casing 90 within the plane of said armature and a resonant diaphragm adapted to be struck by 95 said attaching means.

3. A horn comprising a cuplike casing, an annular magnetic coil in said casing, a ring for retaining said coil in position therein, a flat disk spring, a cuplike armature 100 carried by said spring located in said casing in the plane of said coil and retaining ring, means for attaching said armature to said spring, normally engaging spring contact members located in said casing and a resonant diaphragm adapted to be struck by 105 said attaching means.

4. A horn comprising a cuplike casing, an annular coil in said casing, a flat disk spring, a cuplike armature carried by said 110 spring, means for attaching said armature to said spring, normally engaging spring contact members fixed in said casing and adapted to be disengaged by said armature and spring retaining means, means operable 115 from without the casing for regulating the distance through which the armature moves before said attaching means disengages said normally engaging contact members, and a resonant diaphragm adapted to be struck by 120 said armature and spring attaching means after said contact members have been disengaged.

5. A horn comprising a cuplike casing, an annular magnetic coil in said casing, a flat disk spring, a cuplike armature carried by said spring, means for attaching said armature to said spring, said means comprising a clamping screw having a head at 125 one end engaging one face of said spring 130

disk, said screw extending through said disk and armature, a spacing washer interposed between said spring disk and armature and lock nuts rigidly securing said 5 armature to screw, a pin carried by the opposite end of said screw but insulated therefrom, normally engaging spring contact members fixed in said casing and adapted to be disengaged by the insulated pin on 10 said armature and spring attaching screw, and a resonant diaphragm adapted to be struck by said clamping screw head.

6. A horn comprising a cuplike casing, an annular magnetic coil in said casing, a 15 ring attached to said casing for retaining said coil therein and forming a part of the magnetic field of said coil, a flat disk spring, a cuplike armature fixed to said spring and projecting through said ring into the plane 20 of said coil, means for attaching said armature to said spring, normally engaging spring contact members fixed in said casing within the plane of said cuplike armature, and a resonant diaphragm adapted to be 25 struck by said attaching means.

7. A horn comprising a cuplike casing, an annular magnetic coil in said casing, a ring attached to said casing for retaining said coil therein and forming a part of the magnetic field of said coil, a flat disk spring, a 30 cuplike armature fixed to said spring and projecting through said ring into the plane of said coil, means for attaching said armature to said spring, a pin fixed to said attaching means but insulated therefrom, an insulating disk fixed to said casing and arranged to project into the plane of said armature, normally engaged spring contact members attached to said insulating disk, a 35 resonant diaphragm arranged in parallel with said spring, and an impact receiving member attached to said diaphragm adapted to be struck by said attaching means.

8. A horn comprising a cuplike casing, an annular magnetic coil in said casing, a ring attached to said casing for retaining said coil therein and forming a part of the magnetic field of said coil, a flat disk spring, a 45 cuplike armature fixed to said spring and projecting through said ring into the plane of said coil, means for attaching said armature to said spring, a pin fixed to said attaching means within the plane of said armature, an insulating disk, means securing said disk to said casing, within the plane of said armature, said securing means forming binding posts for current conducting wires to said coil, normally engaged spring contact members attached to said insulating 50 disk, said contact members being adapted to be engaged by the pin on said armature and spring attaching means, a resonant dia-

phragm, and an impact receiving member attached to said diaphragm adapted to be struck by said attaching means.

9. A device of the kind described, comprising a cuplike casing having an annular flange, an annular magnetic coil in said casing, a ring engaging said annular flange on said casing and adapted to retain said coil in position therewith, a disk-like spring engaging at its peripheral margins with the like margin of said ring, a cuplike armature, means attaching said armature to said spring, said armature being located in the 75 plane of said coil and ring, an insulating disk attached to said casing within the plane of said armature, said disk having normally engaging spring contact members, a resonant diaphragm member, a spacing ring separating said spring disk and said diaphragm and engaging with the peripheral margins thereof, a concavo-convex apertured front wall plate engaging at its peripheral margin with the margin of said diaphragm and 80 means for securing the several engaging marginal parts together in proper relative positions.

10. A device of the kind described comprising a cup-like casing, an annular magnetic coil in said casing, a ring engaging said casing and adapted to retain said coil in position therein, a disk-like spring engaging at its peripheral margin with the like margin of said ring, a cuplike armature, 90 means attaching said armature to said spring, said armature being located in the plane of the coil and ring, an insulating disk attached to the casing within the plane of said armature, said disk having normally 95 engaging contact members, a resonant diaphragm member, a spacing ring separating said spring disk and said diaphragm and engaging with the peripheral margins thereof, a concavo-convex apertured front wall 100 plate engaging at its peripheral margin with the margin of said diaphragm, said casing, coil, ring, armature, spring, attaching means, insulating disk and diaphragm all being 105 coaxially arranged relative to each other, and a plurality of clamping screws extending through the several adjacent marginal parts whereby all of said parts are held in proper relative position with respect to each other.

In testimony, that I claim the foregoing as my invention I affix my signature in the presence of two witnesses, this 4th day of December A. D. 1914.

HOMER A. BRETZ.
